UNITED STATES PATENT OFFICE

97,329

DESIGN FOR A DOLL

Chihiro Katagiri, New York, N. Y.

Application September 7, 1935, Serial No. 58,465

Term of patent 7 years

To all whom it may concern:

Be it known that I, Chihiro Katagiri, a citizen of Japan, residing at New York city, county of New York, Borough of Manhattan, and State of New York, have invented a new, original, and ornamental Design for a Doll, of which the following is a specification, reference being had to the accompanying drawing, forming a part thereof.

I claim:

The ornamental design for a doll as shown.

CHIHIRO KATAGIRI.
